UNITED STATES PATENT OFFICE

152,302

DESIGN FOR A UNIT HEATER CASING

James Teague, Chicago, Ill., assignor to Modine
Manufacturing Company, Racine, Wis., a cor-
poration of Wisconsin

Application January 31, 1947, Serial No. 136,557

Term of patent 14 years

(Cl. D81—10)

To all whom it may concern:

Be it known that I, James Teague, a citizen
of the United States, residing at 40 E. Elm, Chi-
cago, in the county of Cook and State of Illinois,
have invented a new, original, and ornamental
Design for a Unit Heater Casing, of which the
following is a specification, reference being had
to the accompanying drawing, forming a part
thereof.

In the drawing:

The figure is a perspective view of a unit heater
casing embodying my design, in which the orna-
mentation continues around the top and side not
shown, in the manner illustrated on the bottom
and side shown.

I claim:

The ornamental design for a unit heater cas-
ing, as shown and described.

JAMES TEAGUE.
